ATTORNEY

UNITED STATES PATENT OFFICE

EMANUEL BEHRMAN, OF NEW YORK, N. Y.

POCKETBOOK

Application filed December 12, 1929. Serial No. 413,448.

This invention relates to new and useful improvements in a lady's pocketbook.

The invention has for an object the provision of a device of the class mentioned which is of simple, durable construction, dependable in use and which can be manufactured and sold at a reasonable cost.

The invention proposes a front member having pockets for holding a cigarette case 10 on its outer surface, together with a loop for holding a cigarette lighter and another pocket for small articles having its opening adjacent a cigarette lighter within the holding loop and normally inaccessible, due to 15 the cigarette lighter preventing bending of the front member while the cigarette lighter is in place, but accessible upon removal of the lighter.

For further comprehension of the invention, and of the objects and advantages thereof, reference will be had to the following description and accompanying drawings forming a material part of this disclosure, and in which:

25 Figure 1 is a perspective view of a ladies' pocketbook constructed according to this invention and shown in closed position.

Figure 2 is a perspective view of the pocketbook shown in Figure 1, but in opened 30 condition.

Figure 3 is a fragmentary vertical sectional view taken on the line 3-3 of Figure 2.

Figure 4 is a front view showing a modified form of the invention.

35 The pocketbook consists of a front forming member 10, having pockets 11 for holding cigarette cases 12, a loop 13 for holding a cigarette lighter 14, and another pocket 15 for small articles having its opening 16 adjacent the cigarette lighter 14 and normally inaccessible, due to the cigarette lighter which prevents bending of the front member 10 while the cigarette lighter is in place but accessible upon removal of the 45 lighter.

The pocketbook is completed with a rear member 17 integral at its bottom with the front member 10. A flexible flap 18 is integral with the top of the rear member 17 and may be folded over the front face of the

front member to close the pocketbook as illustrated in Figure 1. Web pieces 19 are attached between the end edges of the front and rear members 10 and 17 respectively.

The front member 10 consists of an outer sheet 20 and an inner leaf 21. The rear member 17 consists of an outer leaf 22 and an inner leaf 23. The connection at the bottom of the front and rear members is accomplished by the connection of the inner leaves 21 and 23 with each other and the outer leaves 20 and 22 with each other.

55 A row of stitches 24 extend from end to end of the front member 10 at a position substantially at the longitudinal center line thereof and serves to connect the outer and inner leaves 20 and 21 respectively. Rows of transverse stitches 25 and 26 extend from the line of the longitudinal stitches 24 upwards to the top of the front member and 60 serve to connect the inner and outer leaves 20 and 21 respectively.

65 The pockets 11 are formed between the outer and inner leaves 20 and 21 of the front member and the stitches 24, 25 and 26.

70 The pocket 15 is also formed by the outer and inner leaves 20 and 21 respectively and the stitches 24, 25, and 26, but is located between the stitches 25 and 26 while the pockets 11 are disposed on opposite sides of the pocket 15. The outer leaf 20 is cut away, as indicated by reference numeral 27, providing a space for the reception of the cigarette lighter 14. Thus the lighter is disposed substantially within the opening formed by the cut-away portion of the pocket. The loop 13 consists of a horizontal strip held by transverse rows of stitches 28 and 28' onto the inner leaf 21. This provides an opening for the reception of the lighter. A strap 29 is 75 attached between the loop 13 and the inner leaf 21 serving to hold the lighter in place within the loop.

80 A lapel or tab 30 is attached upon the free edge of the flap 18 and may be engaged 85 through a strap 31 forming a loop and attached upon the front of the outer leaf 20 for holding the pocketbook in the closed position. In addition, a snap fastener socket 32 is arranged upon the lapel 30 and is engageable 90

95 100

with a snap fastener stud 33 upon the front face of the outer leaf 20 for holding the pocketbook closed. The main chamber of the pocketbook is indicated by reference numeral 34 and there is another chamber 35 between the outer and inner leaves 22 and 23 respectively.

While the lighter 14 is in place within the loop 13, the pocket 15 is not accessible. The front member 10 cannot be bowed in the region on the lighter for causing the top edge 16 to be bent away from beneath the lighter 14. Upon removal of the lighter, the element which held the front member against bending has thus been withdrawn and it may be slightly bowed so that the pocket 15 is accessible for use.

Figure 4 shows a modified form of the invention wherein two loops 13, 13a are provided for holding a cigarette lighter 14 in one and a perfume atomizer 14a in the other, the pocket 15 having its opening 16 adjacent the articles within said holding loops.

Although I have described my improvements with considerable detail and with respect to certain particular forms of my invention, I do not desire to be limited to such details since many changes and modifications may well be made without departing from the spirit and scope of my invention in its broadest aspect.

Having thus described the invention, what is claimed as new and desired to secure by Letters Patent, is:—

35. 1. In a lady's pocketbook, a front member, pockets for holding cigarette cases on the front thereof, a loop for holding a cigarette lighter, and another pocket for small articles on the exterior of the front member, said pocket having an outer layer cut-away whereby the intermediate portion of the loop is disposed in the recess formed thereby and having its opening adjacent a cigarette lighter within said holding loop, said pocket being normally inaccessible due to the cigarette lighter and the prevention of bending of the front member while the cigarette lighter is in place but accessible upon removal of the lighter.
40. 2. In a lady's pocketbook, a front member, pockets for holding cigarette cases on the front thereof, a loop for holding a cigarette lighter, and another pocket for small articles on the exterior of the front member, said pocket having an outer layer cut-away whereby the intermediate portion of the loop is disposed in the recess formed thereby and having its opening adjacent a cigarette lighter within said holding loop, said pocket being normally inaccessible due to the cigarette lighter and the prevention of bending of the front member while the cigarette lighter is in place but accessible upon removal of the lighter, said front member consisting of an outer and an inner leaf, and means for dividing the space between the leaves into the pockets.
45. 3. In a lady's pocketbook, a front member, pockets for holding cigarette cases on the front thereof, a loop for holding a cigarette lighter, and another pocket for small articles on the exterior of the front member and having its opening adjacent a cigarette lighter within said holding loop, said pocket being normally inaccessible due to the cigarette lighter and the prevention of bending of the front member while the cigarette lighter is in place but accessible upon removal of the lighter, said front member consisting of an outer and an inner leaf, and means for dividing the space between the leaves into the pockets, said outer sheet being cut in the vicinity of the said pocket for small articles by providing a space for the reception of the said cigarette lighter.
50. 4. In a lady's pocketbook, a front member, pockets for holding cigarette cases on the front thereof, a loop for holding a cigarette lighter, and another pocket for small articles on the exterior of the front member and having its opening adjacent a cigarette lighter within said holding loop, said pocket being normally inaccessible due to the cigarette lighter and the prevention of bending of the front member while the cigarette lighter is in place but accessible upon removal of the lighter, said front member being integral at its bottom with a rear member terminating

at its top in a flap adapted to fold over the front of the said front member for covering the pockets.

3. In a lady's pocketbook, a front member, 70 pockets for holding cigarette cases on the front thereof, a loop for holding a cigarette lighter, and another pocket for small articles on the exterior of the front member, said pocket having an outer layer cut-away whereby the intermediate portion of the loop is disposed in the recess formed thereby and having its opening adjacent a cigarette lighter within said holding loop, said pocket being normally inaccessible due to the cigarette lighter and the prevention of bending of the 75 front member while the cigarette lighter is in place but accessible upon removal of the lighter, said front member being integral at its bottom with a rear member terminating 80 in a flap adapted to fold over the front of the said front member for covering the pockets, and means for holding the flap in closed position.

4. In a lady's pocketbook, a front member, 85 pockets for holding cigarette cases on the front thereof, a loop for holding a cigarette lighter, and another pocket for small articles on the exterior of the front member, said pocket having an outer layer cut-away whereby the intermediate portion of the loop is disposed in the recess formed thereby and having its opening adjacent a cigarette lighter within said holding loop, said pocket being normally inaccessible due to the cigarette 90 lighter and the prevention of bending of the front member while the cigarette lighter is in place but accessible upon removal of the lighter, said front member consisting of an outer and an inner leaf, and means for dividing the space between the leaves into the 95 pockets.

5. In a lady's pocketbook, a front member, 100 pockets for holding cigarette cases on the front thereof, a loop for holding a cigarette lighter, and another pocket for small articles on the exterior of the front member and having its opening adjacent a cigarette lighter within said holding loop, said pocket being normally inaccessible due to the cigarette 105 lighter and the prevention of bending of the front member while the cigarette lighter is in place but accessible upon removal of the lighter, said front member consisting of an outer and an inner leaf, and means for dividing the space between the leaves into the pockets, said outer sheet being cut in the vicinity 110 of the said pocket for small articles by providing a space for the reception of the said cigarette lighter.

6. In a lady's pocketbook, a front member, 115 pockets for holding cigarette cases on the front thereof, a loop for holding a cigarette lighter, and another pocket for small articles on the exterior of the front member and having its opening adjacent a cigarette lighter 120

125

within said holding loop, said pocket being normally inaccessible due to the cigarette lighter and the prevention of bending of the front member while the cigarette lighter is 5 in place but accessible upon removal of the lighter, said front member consisting of an outer and an inner leaf, and means for dividing the space between the leaves into the pockets, said outer sheet being cut in the vicinity 10 of the said pocket for the small articles by providing a space for the reception of the said cigarette lighter, the loop for holding the cigarette lighter consisting of a horizontal strip stitched upon the inner leaf of the front 15 member with the cut out portion of the outer leaf.

7. In a lady's pocketbook, a front member, pockets for holding cigarette cases on the front thereof, a loop for holding a cigarette 20 lighter, a loop for holding a perfume atomizer, and another pocket for small articles on the exterior of the front member, said pocket having an outer layer cut-away whereby the intermediate portion of the loop is disposed 25 in the recess formed thereby and having its opening adjacent a cigarette lighter and a perfume atomizer within said holding loops, said pocket being normally inaccessible due to the cigarette lighter and the prevention of 30 bending of the front member while the cigarette lighter is in place but accessible upon removal of the lighter.

8. In a lady's pocketbook, a front member, pockets on the front thereof, a loop disposed 35 at the front member for holding a cigarette lighter or perfume atomizer, and another pocket for small articles on the exterior of the front member, said pocket having an outer layer cut-away whereby the intermediate 40 portion of the loop is disposed in the recess formed thereby and having its opening adjacent the article within said holding loop, said pocket being normally inaccessible due to the article while the article is in place but 45 accessible upon removal of the article.

9. In a lady's pocketbook, a front member, a loop disposed at the front member for holding a cigarette lighter or perfume atomizer, and a pocket for small articles on the exterior 50 of the front member, said pocket having an outer layer cut-away whereby the intermediate portion of the loop is disposed in the recess formed thereby and having its opening adjacent the article within said holding loop, 55 said pocket being normally inaccessible due to the article while the article is in place but accessible upon removal of the article.

Signed at New York, in the county and State of New York, this 30th day of November, 1929.

EMANUEL BEHRMAN.
